CLAIM

The ornamental design for a shoe cabinet, as shown and described.

DESCRIPTION

FIG. 1 is an upper perspective view of a shoe cabinet showing my new design;

FIG. 2 is a lower perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1; and,

FIG. 10 is another perspective view of the shoe cabinet of FIG. 1, shown in an alternate configuration.

The dash-dash broken lines in the drawings depict portions of the shoe cabinet that form no part of the claimed design. The dot-dash broken lines represent boundaries of the enlarged portion that form no part of the claimed design.

1 Claim, 10 Drawing Sheets
